United States Patent Office.

GARRETTSON SMITH AND HENRY BROWN, OF PHILADELPHIA, PENNSYLVANIA, ASSIGNORS TO ABBOTT AND NOBLE, OF SAME PLACE.

Design No. 3,059, dated May 26, 1868; antedated May 5, 1868.

DESIGN FOR AN ILLUMINATING-RING FOR GAS-STOVES.

The Schedule referred to in these Letters Patent and making part of the same.

TO ALL WHOM IT MAY CONCERN:

Be it known that we, GARRETTSON SMITH and HENRY BROWN, of Philadelphia, county of Philadelphia, State of Pennsylvania, have invented or produced a new and original Design for an Illuminating-Ring for Stoves; and we do hereby declare that the accompanying drawing, and the following explanation thereof, form a full, clear, and exact description of the said design.

The drawing represents, in perspective, the illuminating-ring, which consists of a circular tapering casting, having an ornamental lower edge, *a*, and in front a door, *B*, with ornamental frame.

On the side of the casting are also panels, *D*, having ornaments similar to those of the door-frame.

Both doors and door-frames have open spaces for receiving mica.

We claim the design for an illuminating-ring for stoves, substantially as described, and shown in and by the accompanying drawing.

In testimony whereof, we have signed our names to this specification in the presence of two subscribing witnesses.

GARRETTSON SMITH,
HENRY BROWN.
